UNITED STATES PATENT OFFICE.

FREDERICK A. PRESTON, OF HIGHLAND PARK, ILLINOIS, ASSIGNOR TO THE MADDEN COMPANY, OF CHICAGO, ILLINOIS, A CORPORATION OF ILLINOIS.

TRACK-CLAMP.

1,254,847.

Specification of Letters Patent. Patented Jan. 29, 1918.

Application filed June 21, 1916. Serial No. 104,985.

To all whom it may concern:

Be it known that I, FREDERICK A. PRESTON, a citizen of the United States residing at Highland Park, in the county of Lake 5 and State of Illinois, have invented a certain new and useful Improvement in Track-Clamps, of which the following is a full, clear, concise, and exact description.

My invention relates to improvements in 10 track clamps.

It frequently happens during severe floods that railway tracks are washed off of the right of way and are sometimes carried a distance of a mile or more. The present 15 invention contemplates a device whereby the track may be anchored to the road-bed so that in case of floods it will remain substantially in place.

One of the objects of the present invention is to provide such a device which may 20 be applied to rails of different sizes, that is, rails having different sections. Another object is to provide an improved device of such character, which may be readily and 25 quickly applied to the rail base and which will firmly hold the latter. A further object is to provide a device of this character which may be economically manufactured.

In the accompanying drawings I have 30 illustrated several embodiments of the invention.

Figure 1 is an elevation of one form of device, the rail base being in section;

Fig. 2 is a top plan view thereof, with a 35 portion of the rail shown in plan view;

Fig. 3 is an elevation thereof;

Fig. 4 is an elevation of another form of device;

Fig. 5 is a top plan view thereof;

Fig. 6 is an elevation of a further form of device, and

Fig. 7 is a top plan view thereof.

The track clamp shown in Figs. 1, 2 and 3 consists preferably of a malleable iron 45 casting 1, arranged to fit beneath the rail base and having the general form of a yoke composed of a transverse member provided with integral jaws 2-3 at opposite ends thereof. The angle of the jaw 2 corresponds 50 substantially to the angle of the section of standard rail bases. The height of the vertical wall of said jaw is about equal to the height of the edge of rails of the largest size to which said track clamp would or-

dinarily be applied. In other words, the 55 rail 4 in said figures is intended to be the maximum size, in which case the jaw 2 fits firmly against the side of the rail base as shown.

The jaw 3 is larger than the jaw 2 and 60 provides sufficient clearance to permit a wedging member 5 to be driven between it and the adjacent side of the rail base. The wedging surface 6 on the jaw 3 coöperates with the side wedging surface 7 of the 65 wedge and forces the wedge horizontally inward against the side of the rail base. It will be seen that as the wedge is driven into the larger jaw of the yoke it fits firmly 70 against the rail base regardless of the dimensions of the latter within the certain limits. The track clamp is thus adapted for rails of any standard sections within reasonable limits. The height of the vertical wall 8 of the wedge is somewhat less than 75 the height of the edge of the rail of maximum section. As shown in Fig. 1 a clearance is provided between the wedge and the horizontal member 1 of the yoke. If the track clamp is applied to a rail having a 80 thinner base, that is one of less vertical height, this clearance will permit the wedge to be driven farther into the yoke than in the case of a thicker rail. There will also be a slight clearance between the opposite 85 side of the rail base and the opposed walls of the jaw 2. However, the track clamp will be held securely to the rail between the vertical wall of said jaw and the wedge member. In order to prevent a return movement of said wedge, a suitable locking device is provided which may have the form 90 of a cotter pin 9, arranged to be driven through any one of a series of openings 10 in the wedge, thereby locking the latter. 95

The track clamp is located at any suitable point on the rail, preferably between two ties and not necessarily against either tie.

The transverse member 1 is provided with an enlargement 11, having an opening 12 100 through which passes some suitable means for anchoring the track to the road-bed. Such means may have the form of a chain 13, as illustrated in Fig. 1, or a cable or bar, secured to a concrete post embedded in the 105 road-bed or secured to some other permanent fastening.

The form of device shown in Figs. 4 and 5

comprises a transverse member 14, having a jaw 15 at one end and a block 16 at the other end slidable thereon by virtue of an opening in said block through which the end 5 of the transverse member passes. A wedge 17 holds said block against the rail base and permits adjustment of said block to rails of different sizes.

The clamp is connected to a stationary 10 part of the road-bed in the manner previously described.

In Figs. 6 and 7 a further form of track clamp is shown, consisting of a transverse member 18 having a jaw 19 at one end and 15 a block 20 at the other end set into a suitable opening 21 in said member and secured in place by a pin 22, the end of which may be bent to prevent its withdrawal. This form of device is made in such sizes as to fit a 20 certain predetermined rail section.

Although the devices described herein may be conveniently made as malleable castings, they need not necessarily be made of such material, as they may be made as forgings 25 or in some other manner. I do not desire to limit myself to the details of the various devices disclosed, as other forms of the invention may be devised which fall within the scope of the appended claims.

Having thus described my invention, what 30 I claim as new and desire to secure by Letters Patent of the United States is:

1. A track clamp comprising a transverse member having an opening therein adapted 35 to receive a chain or cable, whereby said transverse member may be anchored to the road bed, an integral jaw at one end of said transverse member adapted to fit one side of rail bases of different sections and an adjustable member carried by said transverse member at the other end thereof and ar-

ranged to fit the other side of the said rail bases.

2. A track clamp comprising a transverse member having an opening therein to receive 45 a chain or cable, an integral jaw at one end thereof, a larger integral jaw at the other end thereof, and a wedging member received between said jaw and the rail base side and having an extension in engagement 50 with the top of the rail base.

3. A track clamp comprising a transverse member having an opening therein, a jaw at one end thereof having a vertical wall equal to the maximum thickness of the rails to 55 which it may be applied and having a larger jaw at the other end thereof and a wedge fitting within said larger jaw and having a vertical wall of less height than that of said first jaw. 60

4. A track clamp comprising a transverse member having an opening therein, a jaw at one end thereof having a vertical wall equal to the maximum thickness of the rails to 65 which it may be applied and having a larger jaw at the other end thereof, a wedge fitting within said larger jaw and having a vertical wall of less height than that of said first jaw and a pin for locking said wedge in place.

5. A device of the class described, comprising 70 a transverse member adapted to be wedged into firm frictional engagement with the base of a rail and means for anchoring said transverse member to the road bed.

6. A device of the class described, comprising 75 a transverse member adapted to be frictionally clamped on the base of a rail, and means for anchoring said transverse member to the road bed.

In witness whereof, I hereunto subscribe 80 my name this 6th day of June, A. D. 1916.

FREDERICK A. PRESTON.
